REFRIGERATOR CABINET

Filed Oct. 7, 1940

UNITED STATES PATENT OFFICE

2,319,001

REFRIGERATOR CABINET

Robert A. King, Erie, Pa., assignor to General
Electric Company, a corporation of New York

Application October 7, 1940, Serial No. 360,117

4 Claims. (Cl. 220—9)

My invention relates to refrigerators, and more particularly to refrigerator cabinet construction.

The objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is a front elevational view, partly broken away, showing a refrigerator cabinet embodying the principles of my invention; Fig. 2 is an enlarged perspective partial view illustrating some of the details of my invention; Fig. 3 is an enlarged view of a portion of the retaining strips shown in Figs. 1 and 2; and Fig. 4 is a cross sectional view taken along the line 4—4 of Fig. 3.

Referring to the drawing, I have shown a refrigerator cabinet 10 of the household type having a cold storage compartment 11 closed by a suitable door 12 and a machinery compartment closed by a suitable door 13.

As best seen in Fig. 2, the cabinet includes an outer metallic wall or shell 14 and a metallic inner shell or liner 15 maintained in spaced apart relationship as by means of a plurality of bridge members 16, formed of suitable non-metallic, non-hygroscopic material. I have found that resinous products, such as those known under the names Bakelite, Textolite, etc., are particularly well adapted to this purpose. Suitable thermal insulation 17 is disposed between the walls 14 and 15.

The marginal edge of the outer wall is bent inwardly to provide a flange 18. The marginal edge of the inner liner 15 is formed with a flange 19 opposed to and in substantial alignment with the flange 18. The bridge members 16 are fastened at each end to suitable brackets as indicated by the numeral 20 in any suitable manner as by means of threaded fastening devices 21 extending through a suitable opening in the bracket 20 into engagement with the walls of a suitable hole in the bridge member 16. The brackets may be suitably secured to the liners or walls 14 and 15 in any suitable manner as by welding for example.

In order to close the space between the flanges 18 and 19, I have provided breaker strips 22 extending entirely around the door opening. The breaker strips are preferably formed from a material having the same characteristics as those of the bridge members 16. In order to support

and retain the breaker strips in position, I have provided retaining strips or bezels 23 extending substantially the full length of each longitudinal edge of the breaker strip. The illustrated retaining strips are generally S-shaped in cross section, thereby providing longitudinally extending grooves or pockets 24 and 25 on opposite sides of a central portion 26 for receiving the edge of one of the flanges and an edge of the breaker strip, respectively. In order to grip securely the flanges and breaker strip, the strips are preferably formed from metal having sufficient resiliency to provide a gripping action, but yet having sufficient rigidity to minimize deformation of the strip. I have found relatively thin sheet steel to be satisfactory. The free ends 28 and 28a of the retaining strip are directed inwardly to grip or clip onto the breaker strip and flange, respectively, the inherent resiliency of the material providing a spring-like action enabling ready assembly or disassembly but insuring a secure grip when in use.

In order to increase the rigidity of the retaining strips and thereby strengthen the same in order to prevent bulging of the breaker strips between the ends thereof and yet utilize metal sufficiently thin to permit taking advantage of its resiliency to provide the aforementioned gripping action, I have provided means such as a plurality of spaced-apart projecting members or portions as ribs or corrugations 27 disposed transversely of the strips and extending around the pocket 24 which receives the flange of one of the wall members. As shown in Fig. 4 the ribs or projecting means 27, may be corrugations formed by a drawing operation preceding the bending steps in the construction of the retaining strips. By providing the projecting portions or ribs 27 on the outside of the pocket 24, means is provided for pressing the breaker strip 22 outwardly into engagement with the inturned free edge 28 of the outer pocket 25 of the retaining strip, adding to the security of the assembly and minimizing slipping or rattling of the breaker strip. The outer pocket 25 is formed by bending or displacing inwardly (that is inwardly with respect to the flange 19 after assembly of the wall construction) and then outwardly past the edge of the breaker strip, thereby forming a longitudinally extending beadlike portion which will engage the outer side of the flange 19 in the assembled position of the reinforcing strip. The strip is then directed substantially parallel to the central portion. The inner pocket 24 is formed by bending or otherwise forming the op-

posite edge of the strip into a generally U-shaped loop with the free end thereof directed inwardly toward the central portion 26 in order to permit the utilization of the inherent resilience of the material from which the strip is made. Referring to Fig. 4, it will be seen that the central portion of the strip engages the outer surface of the flange 19 at two spaced apart points, namely, at the beadlike portion and near the base of the inner pocket. The free leg or portion of the inner pocket is so dimensioned that engagement is had with the inner surface of the flange at a point intermediate the places of engagement with the outer surface of the flange, whereby the flange is securely held against slipping and rattling. The breaker strip is also engaged by the assembly strip at three zones. As shown in Fig. 4, the strip will twist or move slightly because of the above-mentioned engagement with the flange, which movement will cause the strip to take a position engaging the inner face of the breaker strip at the projecting portions or at the crown of the corrugations and also adjacent the beadlike portion. The twisting of the strip will cause the free edge of the parallel portion of the strip to engage the outer surface of the breaker strip.

In order to improve the appearance of the retaining strips, I may provide a coat of decorative material on the exposed portions thereof, as, for example, a strip 28 of stainless steel rolled over the exposed edges.

According to one manner of assembly, the retaining strips or clips 23 may be placed on the flanges 18 and 19 respectively, and the breaker strip placed on the central portions 26 of the retaining strips. The retaining strips may then be moved towards each other until the edges of the breaker strip enter the pockets 25 and are firmly engaged by the retaining strips.

The breaker strips and retaining strips are preferably held in place at the ends thereof by means of corner pieces 30 suitably secured as by screws 31 extending through suitable openings in the breaker strips and flanges 18 and 19. The corner pieces 30 also serve to conceal the ends of the breaker strips.

While I have shown and described by invention as applied to a specific refrigerator construction, other modifications will occur to those skilled in the art. For example, instead of providing corrugations 27 for the purposes described, the same results may be obtained by securing a strip of metal to the outer surface of the pocket. Moreover, my invention is equally applicable to the structure of the door 12.

What I claim as new and desire to secure by Letters Patent of the United States is:

1. In a refrigerator cabinet of the type having walls including inner and outer shells with opposed substantially aligned flanges, the edges of said flanges being maintained in spaced-apart relationship, and a relatively rigid breaker strip of thermally resistant material closing the space between said flanges, means extending substantially the full length of each longitudinal edge of said breaker strip for holding said breaker strip in place, said means comprising a relatively resilient retaining strip generally S-shaped in cross section, and having first and second longitudinally extending pockets on opposite sides of a central portion for receiving the edge of one of said flanges and an edge of said breaker strip, respectively, in overlapping relationship, the free edge of said first pocket being directed toward

said central portion, the free edge of said second pocket being displaced inwardly toward said flange, then outwardly past the edge of said breaker strip to form a longitudinally extending beadlike portion, and then substantially parallel to said central portion so that said retaining strip engages the other side of said flange at the free edge thereof and at the beadlike portion and engages the inner side of said flange at the free edge of said first pocket, said first pocket being of a length such that the material adjacent the free edge thereof engages the inner side of said flange intermediate the points of engagement of the central portion of said retaining strip and said flange, whereby said flange is engaged along three spaced apart lines of contact, the resiliency of said retaining strip serving to cause said retaining strip to grip firmly said flange and breaker strip, respectively, the gripping action between said central portion and said flange and said breaker strip, respectively, being the only means for maintaining said breaker strip, said retaining strip, and said flange in assembled relation.

2. In a refrigerator cabinet of the type having walls including inner and outer shells with opposed substantially aligned flanges, the edges of said flanges being maintained in spaced-apart relationship, and a relatively rigid breaker strip of thermally resistant material closing the space between said flanges, means extending substantially the full length of each longitudinal edge of said breaker strip for holding said breaker strip in place, said means comprising a relatively resilient retaining strip generally S-shaped in cross section, and having first and second longitudinally extending pockets on opposite sides of a central portion for receiving the edge of one of said flanges and an edge of said breaker strip, respectively, in overlapping relationship, the free edge of said first pocket being directed toward said central portion, the free edge of said second pocket being displaced inwardly toward said flange, then outwardly past the edge of said breaker strip to form a longitudinally extending beadlike portion, and then substantially parallel to said central portion, means projecting outwardly from said central portion into engagement with said breaker strip at a point spaced from said beadlike portion so that said retaining strip engages the outer side of said flange at the free edge thereof and also at the beadlike portion and engages the inner side of said flange adjacent the free edge of said first pocket, said first pocket being of a length such that the free edge thereof engages the inner side of said flange along a line intermediate the places of engagement of the retaining strip and the flange, said retaining strip engaging the inner side of said breaker strip along a line adjacent said beadlike portion and said breaker strip engaging portions and engaging the outer side of said breaker strip along the free edge of said parallel portion, whereby said retaining strip firmly engages said breaker strip at three zones of contact, respectively, the gripping action between said central portion and said flange and said breaker strip, respectively, being the only means for maintaining said breaker strip, said retaining strip, and said flange in assembled relationship.

3. In a refrigerator cabinet of the type having walls including inner and outer shells with opposed substantially aligned flanges, the edges of said flanges being maintained in spaced-apart relationship, a breaker strip of thermally re-

sistant material closing the space between said flanges, means extending substantially the full length of each longitudinal edge of said breaker strip for holding said breaker strip in place, said means comprising a relatively resilient retaining strip generally S-shaped in cross section, and having longitudinally extending pockets on opposite sides of a central portion for receiving one of said flanges and said breaker strip respectively, the free edges of said retaining strip being disposed to grip said one of said flanges and said breaker strip, respectively, said strip also having a plurality of spaced apart transversely disposed projecting portions arranged on the outside of the pocket receiving said flange, said portions engaging the breaker strip, such engagement causing said retaining strip to take a position in which said breaker strip engages the free edge of the other of said pockets.

4. In a refrigerator cabinet of the type having walls including inner and outer shells with opposed substantially aligned flanges, the edges of

said flanges being maintained in spaced-apart relationship, a breaker strip of thermally resistant material closing the space between said flanges, means extending substantially the full length of each longitudinal edge of said breaker strip for holding said strip in place, said means comprising a relatively resilient retaining strip generally S-shaped in cross section and having longitudinally extending pockets on opposite sides of a central portion for receiving one of said flanges and an edge of said breaker strip, respectively, the free edges of said retaining strip being disposed to grip said one of said flanges and said breaker strip, respectively, said strip also comprising a plurality of spaced-apart transversely disposed corrugations extending around the pocket receiving said flange, the crown of said corrugations engaging the inner side of said breaker strip, such engagement causing said retaining strip to take a position in which said breaker strip engages the free edge of the other of said pockets.

ROBERT A. KING.
